PANEL HEATING ELEMENT
 Giovanni Varionga, Via Bernardino Verra 90,
 Milan, Italy
 Filed Dec. 6, 1960, Ser. No. 74,073
 Claims priority, application Italy Mar. 9, 1960
 1 Claim. (Cl. 165—129)

The present invention relates to panel heating elements, comprising heating medium conducting drawn tubes in combination with metal panels, and presenting the following advantages over the types presently in use:

- (a) High thermal yield,
- (b) Low production cost,
- (c) The possibility of being employed equally well as a ceiling radiating element, or as a vertical wall convector,
- (d) The possibility of easy and economic construction of heating elements of any height whatsoever.

Said invention is fundamentally characterized in that a plurality of equidistant, cylindrical metal tubes in communication with each other through circulating heating water induction or header tubes, and a plurality of suitably folded aluminum plates combine together in a removable manner, by means of intimate mutual surface contact, in such a manner, that, particularly during the maximum heat transmission phase, they cooperate to establish an efficient mechanical engagement between the contiguous tubes and the fixed plates due to the elastic deformation created in said plates. The contact association between the tubes and the plates is established by the suitable type of folding given to the plates, which are furnished with opposed grooves with their surfaces joined to the cylindrical portions of the tube or pipe surfaces facing inwards, and into the spaces between which pipes the plates are forcibly inserted. The cylindrical portions of the tube surfaces which come in contact with the respective grooves of each plate amount to slightly less than half of the total tube surface.

The plates inserted between the contiguous iron tubes traversed by the heating fluid can be made of aluminum sheeting or aluminum alloy folded over on itself like a flattened tube and comprising in correspondence with the opposite plates of lesser dimensions, recesses constituting the contact and engaging grooves for the aforementioned tubes. The edges of the plates folded over on themselves can be brought close to each other, spaced away from each other, or superimposed on each other, and in each of these modifications either free of each other or fixed to each other.

A hood comprised of a tile shaped structure, and longitudinally perforated along part of its length, closes like a cover the upper ends of the aluminum or aluminum alloy plates shaped in the form of a flattened tube, and encloses in its reach at least one of the multiple tubes traversed by the heating element.

The attached drawing and following description of an illustrative embodiment is given purely as an example, and in no way limits the scope of the invention; it shows a practical embodiment of the invention.

FIG. 1 is a front elevational view of part of the heating element;

FIG. 2 is a sectional view on line II—II of FIG. 1;

FIGS. 3 and 4 are respectively a front elevational view and a plan view of the heating element complete with the aluminum plates and hood;

FIG. 5 is an enlarged longitudinal sectional view taken on line V—V of FIG. 3;

FIG. 6 is a cross sectional view to an enlarged scale taken on line VI—VI of FIG. 3, showing the edges of the plates spaced away from each other;

2

FIG. 7 is similar to FIG. 6 but showing the edges of the plates brought close to each other;

FIG. 8 is similar to FIG. 6 but showing the edges of the plates superimposed;

FIG. 9 is similar to FIG. 6 but showing the edges of the plates fixed to each other.

Referring to the drawing, the heating element comprises a system of welded drawn steel tubes, forming a number of vertically disposed tubes 1, connected at their upper extremity to the header delivery pipe 2, and at their lower extremity to the return pipe 3, and a number of aluminum or aluminum alloy plates 4 forced on to or mechanically fixed to, tubes 1, in which tubes 1 the heating fluid flows, the whole forming a panel functioning both by convection and by radiation.

In this manner said panel can sustain all working pressure, and the aluminum plates, the thermal conductivity of which is extremely high, are in close contact with the tubes, whereby the heat of the tubes is efficiently transmitted to the plates with the result that a very high yield of heat from the circulating water is obtained.

Before the aluminum plates 4 are snap mounted on tube 1, a thin film of varnish is applied to the tubes in order to diminish the average width of the air layer which is less conductive than the varnish, and thereby increase the heat transmission from the pipes to the plates. Said heat transmission is further increased when the varnish contains metal powder, for example aluminum.

The aluminum plates 4 are formed as tube shaped sheets, and function as chimneys in such a manner as to induce convection.

In said sheet structure 4, and in order to increase the contact with tubes 1 during the operation of the heating element owing to thermal expansion, grooves 5 are provided on said sheets (FIG. 6) and the surfaces of said grooves are joined to those of contiguous tubes 1.

The covering hood 6 of the head of the plates 4 (FIG. 5) and of the header pipe 2 is provided with oblique holes 7, and is forced on to said plates by means of its edges 8, furnished with suitable grips 9.

It is understood that apart from the employment herein described, other embodiments and applications of the invention can be made, for example, the heating element apart from being used as a vertical wall radiating panel, can be employed for a ceiling, without departing from the invention.

I claim:

A heating device adapted to operate as a radiator and convector in hot water, super heated water or high pressure steam room heating installations, comprising a plurality of equally-spaced vertical cylindrical tubes arranged parallel to each other in a row, a circulating heating medium induction pipe connected to one end of each tube, a return pipe connected to each of the tubes at their other ends, said tubes being in communication with each other through the circulating heating medium induction pipe and the return pipe, and a plurality of detachable heat-radiating panels, each consisting of a flexible aluminum plate folded to a hollow, generally rectangular shape in horizontal cross-section and positioned in coplanar relation and open at their tops and bottoms removably disposed between the tubes and having intimate mutual surface contact with said tubes, in such manner that during the maximum heat transmission phase the tubes and panels unitedly establish an efficient mechanical engagement between the contiguous tubes and the panels due to the elastic deformation created in said panels, each said panel having a front wall, a back wall, and two relatively narrower side walls with beveled corners connecting the front and back walls to the side walls, the back walls lying substantially in the same plane and

the front walls lying substantially in the same plane, each of said back walls having a vertical slot therein extending entirely from top to bottom thereof whereby said panels are resiliently yieldable transversely of said tubes, said side walls having vertical grooves therein engaging said tubes and of a depth to receive substantially half the transverse width of said tubes, said grooves being substantially equally spaced from each of said front and back walls a sufficient distance, at least approximating the diameter of said tubes, to permit sufficient flexing of said side walls to allow insertion and removal of said panels between two adjacent tubes by movement in either direction transversely of the row of tubes, said panels resiliently engaging substantially half the periphery of said tubes when in position therebetween, a thin layer of a heat conductive coating material disposed in said grooves between said panels and the adjacent tubes, and a hood disposed at the upper end of the device into which the

upper ends of said panels are inserted, said hood having depending front and rear edges respectively engaging and securing the upper ends of said front and back walls, said hood being provided with an opening for the discharge of air rising through said panels.
